FOLDING PRIE-DIEU

William F. Liska, Chicago, Ill., assignor to Holland Brass Works, Inc., Chicago, Ill., a corporation of Illinois

Application February 10, 1934, Serial No. 710,655

8 Claims. (Cl. 155—166)

This invention relates to a prie dieu, and particularly to such a device of the character described, which may be readily transported manually from place to place.

5 One object of the present invention is to provide a structure of the character described, which is of suitable size and proportions when in use, and which may be readily folded into a comparatively small space of minimum dimensions for convenient handling and transporting or moving the device from one place to another.

Another object of the invention is to provide a structure wherein all the elements of the structure are permanently connected together and suitably arranged to permit of their being positioned in operative relationship and secured together to provide a safe and efficient structure.

Another object of the invention is to provide a structure wherein the elements comprised therein may be readily moved, with relation to each other, into folded arrangement to provide a package of relatively small size of minimum dimensions for convenient handling in moving or transporting the device from place to place.

25 Another object of the invention is to provide a structure wherein portions of certain of the elements are protected against damage from contact with each other when the device is in folded position.

30 Another object of the invention is to provide a structure wherein the device and surroundings may be suitably illuminated, if desired.

A still further object of the invention is to improve devices of the character described in sundry details hereinafter referred to and particularly pointed out in the appended claims.

One embodiment of the present invention is shown for illustrative purposes in the accompanying drawings, in which:

40 Fig. 1 is a front view of my improved prie dieu illustrating features of the present invention;

Fig. 2 is a sectional elevational view of the structure illustrated in Fig. 1, and taken substantially as indicated by line 2—2 thereof;

45 Fig. 3 is an enlarged fragmentary rear elevational view of a portion of the structure illustrated in Figs. 1 and 2, having portions broken away to illustrate certain of the connecting or locking means;

50 Fig. 4 is a front elevational view of the device shown in folded condition;

Fig. 5 is an enlarged end elevational view, showing the device in folded condition as illustrated, in front view, in Fig. 4;

55 Fig. 6 is an enlarged fragmentary plan sectional

view of the portion of the device illustrating the arrangement of the supporting means and locking means, and taken substantially as indicated by the line 6—6 of Fig. 1;

Fig. 7 is an enlarged fragmentary sectional elevation through a portion of the arm rest, illustrating the lighting arrangement associated therewith, and taken substantially as indicated by the line 7—7 of Fig. 1;

Fig. 8 is a fragmentary sectional elevational view of a portion of the lighting arrangement, taken substantially as indicated by the line 8—8 of Fig. 7; and

Fig. 9 is a fragmentary elevational view, partly in section, of a portion of the arm rest, illustrating the manner of mounting a flood light or the like thereon.

The illustrative embodiment of the present invention shown in the drawings comprises a substantially rectangular frame member indicated, as 20 a whole, by the numeral 11 and constituting a knee rest on which a kneeling pad 12 may be mounted, preferably, adjacent the front edge thereof, and preferably adjacent the respective ends of the knee rest 11 are provided spacing stops 13.

25 Positioned adjacent the rear edge portion of the knee rest 11 and forming a part thereof is an upstanding portion 14 to the upper edge of which a frame constituting an arm rest, indicated as a whole by the numeral 15, is connected by means 30 of a piano hinge 16, and mounted preferably along the upper edge portion of the arm rest 15 is a pad 16a.

Positioned preferably below the pad 16a and extending longitudinally of the arm rest 15 is a lamp 35 housing 17 having brackets 18 mounted therein adapted to receive a plurality of lamps 19.

Formed in the lamp housing 17, adjacent the lamps 19, are a plurality of apertures 20 through which light may be transmitted for illuminating 40 the kneeling pad 12 of the knee rest 11, and formed in the arm rest 15 adjacent the lamp housing are a plurality of openings 21 through which light may be directed to the rear of the prie dieu.

45 For conveniently connecting the lighting system to a source of current supply, the lamps 19 may be provided with flexible conductors or cords 22 having a terminal connection (not shown) by which the lamps may be connected to a wall socket 50 or the like, wherever the prie dieu may be positioned for use.

The arm rest 15, when in use, is intended to occupy a substantially vertical position as illustrated in Figs. 1 and 2, but by reason of the hinge 55

16, the arm rest 15 may be folded down to occupy a position above and in substantially parallel relation with respect to the knee rest 11, as illustrated in Figs. 4 and 5 and by dotted lines in Fig. 5, the spacing stops 13 on the knee rest 11 being adapted to engage the arm rest 15 to maintain the arm rest in spaced relation to the knee rest, and to maintain the lamp housing 17 and arm rest 15 out of contact with the kneeling pad 12 when the knee rest and arm rest are in folded position.

10 The knee rest 11 is shown in the present instance as provided adjacent its respective corners with longitudinally extending leg portions 23, and for supporting the knee rest and arm rest 15 in elevated position, a plurality of supporting frame members or supports indicated as a whole by the numeral 24 are positioned adjacent the respective ends of the knee rest 11 and connected thereto by means of a plurality of links 25 pivotally connected adjacent one of their ends to the frame supports 24 as indicated at 26, and at their opposite ends to the leg portions 23 of the knee rest 11 as indicated at 27.

20 For connecting the frame supports 24 to the arm rest 15 in a manner to retain the arm rest in substantially vertical position, the frame supports 24 are provided adjacent their rear edges with vertically disposed brace portions 28 having inwardly extending lugs 29 formed thereon adjacent their upper ends and adapted to be positioned in apertures 30 formed in the vertical side portions of the arm rest 15, as clearly shown in Figs. 2, 3, and 6, the lugs 29 being provided preferably on their upper sides with notches or recesses 31 adapted to receive spring actuated latches 32 pivotally mounted at 33 on the arm rest, and adapted to be manually operated to remove the latch 32 from the recess 31.

It will be observed that when the frame supports 24 are in their upright or frame supporting position, the supports snugly engage the ends of the knee rest 11 as clearly shown in Fig. 1, and with the upwardly extending brace portions 28 of the frame supports 24 secured to the arm rest 15 by the latch 32 as clearly shown in Fig. 3, the knee rest 11, arm rest 15 and frame supports 24 are secured together against relative movement in a manner to provide a substantially rigid structure.

50 It will be observed by reference, particularly, to Figs. 3, 4, and 5 that the frame supports 24 upon being released from the latch 32 are adapted to be swung downwardly and inwardly as indicated by the dot and dash line in Fig. 3 to a position beneath and in substantially parallel relation with respect to the knee rest 11, and in a manner to occupy a position below the body of the knee rest and above the lowermost side of the leg portion 23 of the knee rest 11, as clearly shown 55 in Figs. 4 and 5 and by dotted lines in Fig. 3. It will be observed that by such an arrangement, the frame supports 24, when folded, are adapted to occupy a position entirely within the lateral and longitudinal dimensions of the knee rest, and 60 that when the frame supports 24 are so positioned and the arm rest 15 is folded down as illustrated in Figs. 4 and 5 and by dotted lines in Fig. 2, the entire structure is adapted to occupy a comparatively small space of minimum dimensions for 65 convenient handling and transporting of the device from one place to another. Furthermore, a device of the construction and arrangement shown and described avoids the possibility of loss or the misplacing of parts such as is prevalent in so-called knock-down structures, for the reason that

in the present arrangement all of the elements are either rigidly or hingedly connected together and relatively movable with respect to each other so that they may be readily secured together in a set-up arrangement which is both substantially rigid and safe.

For mounting a portable lamp or flood light as shown in Fig. 9, the arm rest 15 may be provided with brackets 34, as clearly shown in Figs. 1, 2, and 9, and in which lamp holders 35 may be 10 positioned for supporting a portable lamp 36 as may be desired.

It will be observed from the foregoing description that the present invention provides a novel and efficient structure in a folding prie dieu by which the device may be readily set up for use wherever desired, and which may be readily folded to provide a package of relatively small dimensions for convenient handling in moving or transporting the device from place to place. Furthermore, that suitable means are provided for efficient illuminating of the device and surroundings to insure safety to its users, and that the lighting equipment and portions of the device are suitably protected against damage from contact with other portions thereof.

Obviously, the present invention is not limited to the precise constructions and arrangement shown and described, as the same may be variously modified. Moreover, all the features of the invention need not be used conjointly, as the same may be used to advantage in variously different combinations and sub-combinations.

What I claim as new and desire to secure by Letters Patent is:—

1. In a device of the class described, the combination of an elongated knee rest, a normally upright support having an arm rest at its upper end, said support having apertures formed therein adjacent its opposite ends and hingedly connected to said knee rest adjacent one edge thereof, short supporting members hingedly connected to said knee rest and adapted to be folded into a common horizontal plane beneath the knee rest, said supporting members having brace portions extending upwardly from the knee rest adjacent the rear portions thereof, lugs on said brace portions engageable with the apertures formed in said support, and means on said support engageable with said lugs of the brace portions for securing the arm rest support to said brace portions and maintaining the knee rest, arm rest and supporting members in fixed relation with respect to each other.

2. In a device of the class described, the combination of an elongated knee rest, a vertically disposed support carrying an arm rest at its upper end hingedly connected to said knee rest adjacent one edge thereof, said arm rest support having vertically disposed flanges at its sides having elongated apertures formed therein, short supporting members hingedly connected to said knee rest and foldable into a common plane beneath the knee rest, said supporting members having upwardly extending brace portions, vertically disposed elongated recessed lugs on said brace portions engageable with said apertures, and spring actuated means on said arm rest support engageable with the recesses in said lugs for securing the arm rests to said brace portions and maintaining the knee rest, arm rest and supporting members in relatively fixed position with respect to each other.

3. In a device of the class described, the combination of an elongated knee rest, a support

carrying an arm rest adjacent its upper end hingedly connected to said knee rest adjacent one edge thereof, said arm rest support having apertures formed therein at opposite sides thereof, a plurality of relatively short supporting members positioned, respectively, adjacent the ends of said knee rest, a plurality of links hingedly connected to said knee rest and said supporting members, said supporting members being adapted to be folded downwardly and inwardly into a common plane beneath said knee rest and having brace portions extending upwardly from the knee rest adjacent their rear end portions, inwardly extending recessed lugs on said brace portions engageable with the apertures formed in the said arm rest support, and manually operable spring actuated latches on said arm rest support engageable with the recesses in the lugs of the brace portions of the supporting members for securing the arm rest support to said brace portions and maintaining the knee rest, arm rest and supporting members in fixed relation with respect to each other.

4. In a device of the class described, the combination of an elongated knee rest adapted to occupy a substantially horizontal position, a support carrying an arm rest at its upper end hingedly connected to said knee rest adjacent the rear edge thereof and adapted to occupy a substantially vertical position with respect thereto and to be swung down to a position above and in substantially parallel relation to said knee rest, relatively short supporting members hingedly connected to said knee rest adjacent the ends thereof and adapted to be folded into a common plane beneath the knee rest, cooperable means on said supporting members and arm rest support for securing the supporting members and arm rest support together and maintain the knee rest, arm rest and supporting members in fixed relation to each other, a lamp housing on said arm rest and spacing stops on said knee rest engageable with said arm rest support for maintaining said lamp housing and arm rest in spaced relation to said knee rest when the arm rest support is positioned above and in substantially parallel relation thereto.

5. In a device of the class described, the combination of an elongated knee rest adapted, normally, to occupy a substantially horizontal position and having a kneeling pad thereon, a support carrying an arm rest at its upper end hingedly connected to said knee rest adjacent one edge thereof and adapted, normally, to occupy a substantially vertical position with respect thereto and to be swung down to a position above and in substantially parallel relation to said knee rest, short supporting members hingedly connected to said knee rest adjacent its ends, cooperable means on said supporting members and arm rest support, respectively, for securing the supporting members and arm rest support together and maintaining the knee rest, arm rest and supporting members in fixed relation with respect to each other, a transversely inclined pad on said arm rest and extending forwardly from adjacent the upper edge thereof and of said support, a lamp housing on said arm rest below said last-mentioned pad, and spacing stops on said knee rest engageable with said arm rest support adjacent its ends for maintaining said lamp housing and arm rest in spaced relation to said kneeling pad and knee rest when the arm rest support is positioned above and in substantially parallel relation with respect to the knee rest.

6. In a device of the class described, the combination of an elongated knee rest adapted, normally, to occupy a substantially horizontal position and having a kneeling pad thereon, an elongated support carrying an arm rest at its upper end and being of a length substantially equal to that of said knee rest, said arm rest support having openings formed therein adjacent its upper edge and being hingedly connected to said knee rest adjacent one edge thereof and adapted, normally, to occupy a substantially vertical position with respect thereto and to be swung down to a position above and in substantially parallel relation to said knee rest, short supporting members having upwardly extending brace portions thereon and hingedly connected to said knee rest, cooperable means on said brace portions and arm rest support, respectively, for securing the supporting members and arm rest support together when the latter is in its vertical position and for maintaining the knee rest, arm rest and supporting members in fixed relation with respect to each other, a transversely inclined pad on said arm rest extending forwardly from adjacent the upper edge thereof, an apertured lamp housing on said arm rest adjacent the openings formed in said arm rest support and below said last-mentioned pad, spacing stops on said knee rest adjacent the ends thereof and engageable, respectively, with said arm rest support adjacent its ends for maintaining said lamp housing and arm rest in spaced relation to said kneeling pad and knee rest when the arm rest support is positioned above and in substantially parallel relation with respect to the knee rest.

7. In a folding prie dieu, the combination of an elongated knee rest adapted to occupy a substantially horizontal position, a support carrying an arm rest at its upper end hingedly connected to said knee rest adjacent the rear side thereof and adapted to occupy a substantially vertical position with respect thereto and to be swung down to a position above and in substantially parallel relation to said knee rest, relatively short supporting members hingedly connected to said knee rest adjacent the ends thereof and adapted to be folded into a common plane beneath the knee rest, and cooperable means on said supporting members and arm rest support for securing the supporting members and arm rest support together and maintain the knee rest, arm rest and supporting members in fixed relation to each other.

8. In a folding prie dieu, the combination of an elongated knee rest adapted to occupy a substantially horizontal position, a support carrying an arm rest at its upper end hingedly connected to said knee rest adjacent the rear side thereof and adapted to occupy a substantially vertical position with respect thereto and to be swung down to a position above and in substantially parallel relation to said knee rest, a plurality of links pivotally connected, respectively, at one of their ends to said knee rest adjacent the respective ends thereof, relatively short supporting members pivotally connected, respectively, to the opposite ends of said links adjacent the respective ends of said knee rest and adapted to be folded into a common plane beneath the knee rest, and cooperable means on said supporting members and arm rest support for securing the supporting members and arm rest support together and maintain the knee rest, arm rest and supporting members in fixed relation to each other.
